ATTORNEY

UNITED STATES PATENT OFFICE.

CHARLES H. WISE, OF OIL CITY, PENNSYLVANIA.

RAILWAY-TIE AND FASTENER.

1,249,876.

Specification of Letters Patent. Patented Dec. 11, 1917.

Application filed March 10, 1917. Serial No. 153,908.

To all whom it may concern:

Be it known that I, CHARLES H. WISE, a citizen of the United States, residing at Oil City, in the county of Venango and State of Pennsylvania, have invented certain new and useful Improvements in Railway-Ties and Fasteners, of which the following is a specification.

My invention relates to railway ties and fasteners and has for its primary object to provide a tie and fastener which will be strong, durable, and effective and which will retain the rails against vibration.

Another important object of the invention is to provide a rail fastening which may be readily engaged or disengaged from the rail with a minimum physical effort.

Another important object is to employ a rail fastening of this character, which may be used in conjunction with any type of rail now in use.

It is another object to provide a railway tie fastening of this general character which is simple in construction, consisting of few parts, is inexpensive to manufacture, and which may be easily placed in operative position.

The invention consists of the novel arrangements and combinations of co-operating elements which will be hereinafter specifically set forth in the following description and specifically defined in the appended claims.

In the drawings wherein my improved construction is illustrated:—

Figure 1 is a plan view of the railway tie and fastener constructed in accordance with my invention,

Fig. 2 is a side view of the same,

Fig. 3 is a sectional view,

Fig. 4 is a transverse sectional view through a slightly modified form of the railway rail fastener, and

Fig. 5 is a plan view of the same.

In the drawings in which like characters of reference designate similar and like parts: the numeral 5 designates my improved cross-tie which consists of a base 6, a web 7, and a horizontally disposed flange 8. As a whole, this cross-tie is I-shaped in cross section and is cast from the usual strong metal. The flange 8 is adapted to support the railway rails, one of which is herein illustrated and designated by the numeral 9. This rail is of conventional construction and as the same

forms no part of the invention, it will only be set forth in a general way.

The specific construction of my improved fastening will now be described in full. In ordinary use there are two of these fastenings employed for each cross-tie.

The numeral 10 designates a base plate of the improved fastening which is formed from metal, possessing the desired strength and durability. The transverse edges of this plate are bent upon themselves as at 11 and extended inwardly and toward each other and provide clips 12 which are adapted for engagement with the horizontal portion or tread 8 of the cross-tie. Formed with one of the longitudinal edges of this plate 10 or otherwise secured, is a rail engaging clamp 13 which is adapted to overlie and engage the base of the rail.

Formed upon the inner face of the plate 10 is a socket 14 which receives a resilient expansible coil spring 15. Positioned in the socket and engaging the coil spring and normally urged outwardly by the same, is a locking dog 16 which is adapted to enter an opening in the tread or horizontal portion 8 of the cross-tie to retain the fastening into engagement with the railway rail and this cross-tie. In this case, only one of the sockets and locking dogs is illustrated but it will be understood that any number of them may be employed.

In Figs. 4 and 5 I have shown a slightly modified form of the fastening. In this form the plate 10 above described is employed and is provided with a socket 17 which extends clear through the plate 10. Mounted therein is a coil spring 18 which bears against a pin or locking dog 19 which is adapted to be received in an opening in the tread of the cross-tie. This locking dog 19 carries a transversely extending handle 20 which extends through longitudinal slots in the socket 17 the purpose of which is to retract the locking dog from the opening in the cross-tie.

From the above disclosure it will be seen that by simply moving the locking dog or bolt within the socket the plate 10 may be mounted in position on the tread of the cross-tie and the clamping member 15 engaging with the tread of the rail and upon releasing the locking dog or bolt, it will enter the opening in the cross-tie and retain the fastening against movement. It should

also be noted that the form shown in Figs. 4 and 5 may be disconnected from the rail by simply grasping the handle 20 and restricting the locking dog or bolt 19 and 5 thereby permitting the fastening to be slid off the cross-tie.

This disclosure is merely illustrative and I do not wish to be limited to the exact details and arrangement of the forms herein 10 specified, but that I will make such legitimate changes and modifications that may fall within the scope of the herewith appended claims.

What is claimed is:—

- 15 1. The combination with a substantially I-shaped cross-tie, of a railway fastening comprising a plate, a rail clamping member carried thereby, and a resiliently retained locking member carried by the plate and engaged with the cross-tie.
- 20 2. A railway rail fastening, a plate, rail engaging means carried thereby, clips also carried by the plate and adapted for engagement with the cross-tie, and a resiliently 25 actuated locking dog carried by the plate

and adapted for locking engagement with the tie.

3. A rail fastening comprising a plate, the transverse edges of the plate being bent and extended inwardly to provide engaging 30 clips, a rail engaging clamp formed with the plate, a socket carried by the plate, and a resiliently actuated locking dog mounted in the socket and adapted for locking engagement with the cross-tie. 35

4. The combination with a cross tie having a socket formed in the upper surface thereof, of a rail clamp slidably mounted on the tie and provided with a socket, and a latch resiliently mounted in said socket 40 and adapted to automatically engage the socket in the tie, when the clamp is in a rail abutting position.

In testimony whereof I affix my signature in presence of two witnesses.

CHARLES H. WISE.
